ABSTRACT OF THE DISCLOSURE

A process for heating liquid mixtures having components which react to form undesired products during heating. The mixture is heated by application of heat through heating surfaces in contact with the liquid mixture. The temperature of the heating surfaces is maintained at a predetermined differential relative to the boiling point of the mixture, to limit the production of undesired products to a minimum during heating.

BACKGROUND OF THE INVENTION

This invention relates generally to processes for heating liquid mixtures and more particularly to processes for heating liquid mixtures having components which react during heating with the formation of undesired products.

As an example of a mixture producing undesired products during heating, unpretreated heavy condensates of cracking gases, mainly C_4 , C_5 , and cracked gasoline fractions, contain substances, such as butadiene, cyclopentadiene and styrene, which tend to form during heating, latex- or cork-like polymerizes. These polymerizes form deposits in feed conduits and on heating surfaces of forced circulation evaporators. The distillation columns therefore must be provided with interchangeable evaporators having removable plates, so that, upon interchange, the plates can be removed from the "down" evaporator and the deposits mechanically removed therefrom. In case of forced circulation evaporators, shutdown and cleaning is normally required after an operating period of a few weeks.

Another example of liquid mixtures yielding undesired products during heating is the regeneration of di- or triethylene glycol to remove water therefrom. In such a case, if the evaporator temperature is not regulated properly, a reaction takes place in which two moles of glycol are condensed, giving rise not only to a loss in glycol, but also to the production of more water.

SUMMARY OF THE INVENTION

An object of this invention, therefore is to provide a method for heating liquid mixtures, wherein undesired products are formed during evaporation, which overcomes the problems of the prior art by inhibiting such formation. Another object is to provide a method of increasing the efficiency and/or extending the operating time of such heating devices with an attendant saving in cost and equipment.

These objects are attained, in accordance with this invention, by maintaining the heating surfaces of the liquid mixture heating apparatus at predetermined desired temperature relative to the boiling temperature of the liquid being heated. The desired temperature differential is a function of the energy of activation of the reaction which forms the undesired products.

These and other objects of the invention will become

better understood to those skilled in the art by reference to the following detailed description when viewed in light of the accompanying drawings, wherein:

BRIEF DESCRIPTION OF THE DRAWINGS

5 FIG. 1 is a non-dimensional graph of the amount of undesired products formed per unit time as a function of temperature differential between the heating surface and the liquid mixture; and

10 FIG. 2 is a plot of the desired heating surface temperature and the heating surface temperature differential relative to the temperature of the liquid mixture for liquid mixtures of different boiling points as a function of the energy of activation for the reaction which forms the undesired products.

DESCRIPTION OF THE PREFERRED EMBODIMENT

In accordance with this invention, it has been discovered that in heating liquid mixtures of the type described there is a relationship between the temperature differential between the heating surface and the boiling point of the liquid mixture and the rate of production of undesired products, which relationship is a function of the energy of activation of the reaction which forms the undesired products.

This relationship is thought to derive from the following considerations:

$$(1) \dot{M} = \int \dot{c}_i dV_H [\text{kmol/sec.}]$$

30 wherein: (I)

$\dot{M}$ is the quantity of undesired products, formed per unit time in a heating device;

$\dot{c}_i$ is the speed of formation of the undesired products; and

35 V_H is the volume of the heating device.

In case of the customarily employed tubular evaporators with close grouping of the heating surface, a simplification can be made as follows:

$$40 (1') \dot{M} = \dot{c}_{i(T_H)} \cdot V_H$$

wherein: $\dot{c}_{i(T_H)}$ represents the speed of formation of the undesired products at a constant temperature T_H of the heating surfaces.

45 Equation 1' reveals that $\dot{M}$ increases with the increasing volume V_H , as long as $\dot{c}_i$ and T_H remain unchanged.

(II) The volume V_H is, however, proportional to the area of the heating surface, H_H , which latter depends in turn, where a specific amount of heat Q is to be transmitted, only on the difference between the temperature of the heating surface T_H and the boiling temperature of the liquid, T , as follows:

$$55 H_H = \frac{Q}{\alpha(T_H - T)}$$

wherein α =heat transfer coefficient.

Since the heating surface H_H varies with the volume by a factor of proportionality $s = V_H/H_H$, the following 60 applies:

$$(2') V_H = s \frac{Q}{\alpha(T_H - T)}$$

65 As Equation 1' demonstrates, $\dot{M}$ increases with V_H , V_H , however, is directly proportional to the heating surface H_H and inversely proportional to the temperature difference $T_H - T$. $\dot{M}$ therefore increases with decreasing temperature differential $T_H - T$, as long as the dependence of the reaction speed $\dot{c}_i$ on the temperature can be neglected.

70 (III) The speed of formation of the undesired prod-

3

ucts $\dot{c}_i$, however, increases with increasing temperature T_w in accordance with the Arrhenius equation:

$$(3) \quad \dot{c}_i = k'_{\circ} e^{-\frac{E}{RT_w}} \left[\frac{\text{kmol}}{\text{m}^3 \text{ sec.}} \right]$$

wherein

E =energy of activation of the reaction forming the undesired products;

R =general gas constant;

$k'_{\circ}$ =a constant (experimentally determined; see John H. Perry, "Chemical Engineers' Handbook," Third Ed., McGraw-Hill Book Co. Inc., 1950, pp. 323-324).

E can be predicted in simple reactions by reference to standard handbooks; however, in more complicated reactions, other means of determination must be referred to. In heating processes where, for example, polymerization is to be avoided, the determination of E causes particular difficulties since the composition of the polymerizes and the existence of numerous reaction stages, namely starting reactions, growth reactions and chain breaking reactions, cannot be accurately determined due to the multitude of monomers present in these mixtures.

During the evaluation of results in connection with plants for such processes, it has been found, however, that the important reaction in the encrustation of the heating surfaces is in the starting reaction of polymerization, namely the radical formation by dissociation (i.e. $(\text{CH}_3)_3\text{C}-\text{O}-\text{O}-\text{C}(\text{CH}_3)_3 \rightarrow 2(\text{CH}_3)_3\text{C}-\text{O}\cdot$ or $\text{CH}_2=\text{CH}-\text{CH}=\text{CH}_2 \rightarrow 2\text{CH}_2=\text{CH}\cdot$) with its attendant high energy of activation. The energy of activation of the dissociation of di-tert.-butyl peroxide $(\text{CH}_3)_3\text{C}-\text{O}-\text{O}-\text{C}(\text{CH}_3)_3$ is, for example, on the order of magnitude of 36,000 kcal./kmol. In this reaction, the controlling value of E then has been found to be 36,000 kcal./kmol (see Frost and Pearson, Kinetik und Mechanismen homogener chemischer Reaktionen, Verlag Chemie, Weinheim/Bergstrasse, 1964, pp. 340-348).

In addition to polymerization reactions, condensation reactions can also lead to the formation of undesired products. During the regeneration of di- or triethylene glycol which has absorbed water while being used as a drying agent and from which the water must be driven out by heating, two molecules of the glycol are chemically added to each other, with the evolution of water. Although no solid products result from this reaction, the consequences are a loss in glycol, as well as the reformation of water. The quantity of these undesired products can likewise be maintained at a minimum if the evaporator temperature is regulated in accordance with this invention.

In a similar manner, the required energy of activation E can be determined for other liquid mixtures by analysis and/or past experience.

(IV) If, for V_H , the value from Equation 2' is inserted in Equation 1', and for $\dot{c}_i$ the value from Equation 3, the following results:

$$(4) \quad \dot{M} = C \frac{e^{-\frac{E}{RT_w}}}{T_w - T} \text{ with } C = \frac{k'_{\circ} Q S}{\alpha}$$

It has been found that this function has a pronounced minimum for:

$$(4') \quad T_{wdes} - T = \frac{T_{wdes}^2 R}{E}$$

or, in terms of T_{wdes} :

$$(4'') \quad T_{wdes} = \frac{1 - \sqrt{1 - 4 \frac{R}{E} T}}{2 \frac{R}{E}}$$

wherein T_{wdes} is the desired heating surface temperature for production of minimum deposits.

4

Without being bound by explanation, it is thought that the above minimum occurs at the temperature T_{wdes} , because, at that temperature, the decrease of $\dot{M}$ with increasing temperature T_w resulting from the proportionality between $\dot{M}$ and the reciprocal of the difference between the heating surface temperature and the boiling temperature

$$\frac{1}{T_w - T}$$

(see Equation 2'), is balanced by the increase of $\dot{M}$ due to the increasing speed of formation of the deposits caused by the increasing heating surface temperature T_w .

In FIG. 1, a dimensionless representation of Equation 4 for constant evaporation temperature is illustrated, wherein $\dot{M}/\dot{M}_{\min}$ is plotted against

$$\frac{T_w - T}{T_{wdes} - T}$$

In this connection $\dot{M}_{\min}$ is obtained by inserting the expression for T_{wdes} from Equation 4'' into Equation 4.

From FIG. 1, it can be seen how the energy of activation influences deviation from T_{wdes} . For values of the abscissa above 1, $\dot{M}/\dot{M}_{\min}$ increases more rapidly with increasing ratio of the energy of activation E to the reference value $E_{\circ}$ (assuming $E_{\circ}$ to be 10,000 kcal./kmol).

From FIG. 2, the values for $T_{wdes} - T$ (ordinate) and T_{wdes} (abscissa) are plotted as related in accordance with Equation 4', to a given boiling temperature T and a given energy of activation E. Using the numerical values $R=1,986$ kcal./kmol °K. and $E=35,000$ kcal./kmol, the desired range is obtained from Equation 4'':

$$T_{wdes} = \frac{1 - \sqrt{1 - 2.27 \cdot 10^{-4} \cdot T}}{1.135 \cdot 10^{-4}} \pm 1$$

This range is characterized in FIG. 2 by the shaded area. Although T_{wdes} is indicated as ± 1 , for better results it is ± 0.5 , more preferably ± 0.2 . On the other hand, T_{wdes} can also be as high as ± 3 , or higher, while obtaining substantial benefits of the invention.

If the mixture to be rectified boils, for example, at 373° K., and the chemical reaction which is primarily responsible for formation of the undesired products has an energy of activation E of 40,000 kcal./kmol, then, from Equation 4' or from FIG. 2, $T_{wdes} - T$ is 7.2° C. and T_{wdes} is 380.2° K. In order to restrict deposits to a minimum, the heating surface of the evaporator must be maintained at the temperature of 380.2° K.

The evaporators used in carrying out the invention are described in "Standards of Tubular Exchanger Manufacturers Association," 4th ed., 1959, especially types AEL and BEM on p. 2. The materials are listed on p. 16 (copper and copper alloys, carbon steel, aluminium and aluminium alloys).

The difference between the temperature of the heating surface, T_w , and the boiling temperature of the liquid, T, until now has usually been kept at about 40-60° C., in order to have a high heat transfer velocity, that is to keep small the heating surface of the evaporator.

The mean boiling temperature of a liquid mixture is the mean value of the boiling temperatures on the upper level and on the bottom of that liquid mixture in the evaporator.

The effectiveness of prior art evaporators presently in service can also be determined from FIGS. 1 and 2. In order to explain this feature, the following example is set forth: Assume that the mixture to be evaporated has an average boiling temperature T of 393° K., an energy of activation of the reaction causing the formation of the undesired products E of 35,000 kcal./kmol, and a temperature of the heating surface T_w of 415° K. From

FIG. 2, $T_{Wdes} - T$ is therefore 9.0° and T_{Wdes} is 402° K., as indicated by dashed line. If the following ratio

$$\frac{T_w - T}{(T_{Wdes} - T)} = \frac{415 - 393}{9.2} = 2.4$$

results, then it can be seen from FIG. 1, as indicated by dashed line, that the amount of deposits actually formed is approximately 1.6 times greater than the amount which would result at a heating surface temperature of 402° K.

Accordingly, with the aid of this invention, the amount of undesired products formed per unit of time can be restricted to a minimum by setting the desired temperature T_{Wdes} for the heating surface of the device. If evaporators, for example, are operated in accordance with this invention, the operating time can be increased by a multiple, and in many cases, cleaning is required only on the occasion of a general shutdown of the entire plant, for example, every one to two years, so that auxiliary evaporators are dispensed with.

Examples for calculation of evaporators according to the invention:

(1) LIQUID MIXTURE.—DEPROPANIZER BOTTOMS

	Weight percent
C_3 's	0.02
C_4H_6	25.74
C_4H_8	59.99
C_4H_{10}	4.88
C_5	7.34
C_6	1.99
C_7+	0.04

$p_1 = 16$ ata.
 $T_1 = 361^\circ$ K.
 $\alpha_{11} = 1100$ kcal./m.² h. $^\circ$ C.
 $\alpha_{a1} = 3000$ kcal./m.² h. $^\circ$ C.

(2) LIQUID MIXTURE.—LOW PRESSURE STRIPPER BOTTOMS

	Weight percent
C_4H_6	14.11
C_4H_8	34.68
C_4H_{10}	3.19
C_5	14.14
C_6	23.86
C_7/C_8	10.01
C_9+	0.01

$p_2 = 7$ ata.
 $T_2 = 348^\circ$ K.
 $\alpha_{12} = 700$ kcal./m.² h. $^\circ$ C.
 $\alpha_{a2} = 3000$ kcal./m.² h. $^\circ$ C.

The values of the heat transfer coefficient α for a given evaporator and liquid are tabulated in "VDI Wärmeatlas Berechnungsblätter für den Wärmeübergang," VDI Verlag Düsseldorf.

In case of both examples the reaction causing polymerisation is assumed to be the formation of radicals from peroxides (see col. 5); the energy of activation therefore is $E = 35,000$ kcal./kmol. As discussed in col. 8, the temperature T_{Wdes} is calculated from Equation 4' or FIG. 2 respectively:

$$T_{Wdes1} = 368.5^\circ$$
 K.; $T_{Wdes2} = 354.5^\circ$ K.

In order to calculate the temperature of the heating steam now, the boiling temperature of the liquid, T , and the temperature of the heating surface, T_{Wdes} , are plotted against $1/\alpha$, $1/\alpha_1$ (inner side, tube) and $1/\alpha_a$ (outer side, shell) extending in opposite directions from the wall, as is seen from FIG. 3. The wanted value, T_{st} , that is the corresponding condensation temperature of the heating steam, is given by the point of intersection of the $1/\alpha_a$ ordinate with the straight line through T and T_{Wdes} . It is seen that

$$T_{st1} = 371^\circ$$
 K.; $T_{st2} = 356^\circ$ K.

The preceding examples can be repeated with similar success by substituting the generically or specifically de-

scribed reactants and/or operating conditions of this invention for those used in the preceding examples.

From the foregoing description, one skilled in the art can easily ascertain the essential characteristics of this invention, and without departing from the spirit and scope thereof, can make various changes and modifications of the invention to adapt it to various usages and conditions. Consequently, such changes and modifications are properly, equitably, and intended to be, within the full range of equivalence of the following claims.

What is claimed is:

1. In a process for heating a liquid mixture having components which react to form undesired products during heating by application of heat through a heating surface in contact with the mixture, the improvement wherein in said heating surface is maintained at a temperature T_{Wdes} according to the following relationship

$$T_{Wdes} = 1 - \sqrt{\frac{1 - 4 \frac{R}{E} T}{2R/E}} \pm X$$

wherein

T = mean boiling temperature in $^\circ$ K. of the liquid mixture;

R = general gas constant;

E = energy of activation of the reaction forming the undesired products; and

X = a permissible deviation of not more than 3° K.

2. In a process of distilling unpretreated heavy condensates of cracking gas in a distillation column provided with an evaporator, the improvement comprising the step of minimizing the polymerization of constituents of the condensates of the gases by maintaining the heating surfaces of said evaporator at a temperature T_{Wdes} in accordance with the following relationship

$$T_{Wdes} = 1 - \sqrt{\frac{1 - 4 \frac{R}{E} T}{2R/E}} \pm X$$

wherein

T = mean boiling temperature in $^\circ$ K. of the liquid mixture;

R = general gas constant;

E = energy of activation of the reaction forming the undesired products; and

X = a permissible deviation of not more than 3° K.

3. A process as described by claim 1 wherein said liquid mixture is depropanizer bottoms.

4. A process as described by claim 1 wherein said liquid mixture is low pressure stripper bottoms.

5. A process as described by claim 1 wherein X is $\pm 1^\circ$ K.

6. A process as described by claim 1 wherein X is $\pm 0.5^\circ$ K.

7. A process as described by claim 1 wherein X is $\pm 0.2^\circ$ K.

8. A process as described by claim 2 wherein X is $\pm 0.2^\circ$ K.

9. A process as described by claim 3 wherein X is $\pm 0.2^\circ$ K.

10. A process as described by claim 4 wherein X is $\pm 0.2^\circ$ K.
